DESIGN FOR A TOWEL BAR BRACKET

Harold Van Doren, Philadelphia, Pa., assignor to Gerity-Adrian Manufacturing Corporation, a corporation of Michigan

Application November 9, 1944, Serial No. 116,236

Term of patent 14 years

(Cl. D33—16)

To all whom it may concern:

Be it known that I, Harold Van Doren, a citizen of the United States, residing at Philadelphia, in the county of Philadelphia and State of Pennsylvania,
have invented a new, original, and ornamental Design for a Towel Bar Bracket, of which the following is a specification, reference being had to the accompanying drawing, forming part thereof.

Figure I is a plan view of a towel bar bracket
showing my new design;

and

I claim:

The ornamental design for a towel bar bracket,
substantially as shown.

HAROLD VAN DOREN.
